CLAIM

The ornamental design for a contoured shoe lace and personal item holder, as shown.

DESCRIPTION

FIG. 1 is a top perspective view of a shoe lace container showing our new design;

FIG. 2 is a front elevational view thereof;

FIG. 3 is a rear elevational view thereof;

FIG. 4 is a bottom plan view thereof;

FIG. 5 is a side elevational view taken from the right end of FIG. 2; and,

FIG. 6 is a top front perspective view showing the container open.
